United States Patent Office

Des. 227,674
Patented July 10, 1973

227,674

REEL FOR MAGNETIC TAPE

Horace T. Montgomery, Mission Viejo, and Hormoz Rafaat, Corona Del Mar, Calif., assignors to Memorex Corporation, Santa Clara, Calif.

Filed Sept. 1, 1971, Ser. No. 177,194

Term of patent 14 years

Int. Cl. D14—01; D16—05
U.S. Cl. D26—14 B

FIG. 1 is a top plan view of a reel for magnetic tape embodying our new design;

FIG. 2 is a front elevational view thereof; and

FIG. 3 is a bottom plan view thereof.

We claim:

The ornamental design for a reel for magnetic tape, substantially as shown.
